SAFETY COUPLING FOR SCREW JOINTS

Julius S. Beck, Los Angeles, Calif., assignor to
James A. Kammerdiner, Los Angeles, Calif.

Application February 24, 1933, Serial No. 658,292

6 Claims. (Cl. 255—27)

This invention relates to a coupling adapted for placing in a string of rods, or a tubular string of pipe and capable of use to clutch the joint sections together or release them by longitudinal positioning of the members of the coupling.

As illustrative of a specific embodiment of the invention, a coupling adaptable for use in well drill pipe employed in rotary drilling is described in the subjoined specification. In the operation

10 of such strings of drill pipe, it is desirable and the usual practice to provide tool joints at intervals which may be readily "broken" or uncoupled when desired. Right hand threads are commonly employed in the tool joints. If it is

15 desired to break a joint, it is the conventional practice to back up to the left. However, with a number of tool joints in the string, it is impossible to predetermine which joint will be uncoupled. It is understood that for certain oper-

20 ations such as fishing, left hand threaded tool joints are employed. To uncouple a string having left hand threaded tool joints, uncoupling may be effected by backing up to the right. As with the right hand threaded tool joints, it is

25 impossible to predetermine at what joint uncoupling will occur in left hand threaded tool joints. It is often desirable in wells to break the joint at a particular place. For illustration, with a rotary boring tool at the end of a drill string,

30 the boring tool may become stuck and it is found advisable to disconnect the drill string immediately above the boring tool. This is attempted by backing off. However, in most instances the drill string uncouples immediately below the ro-

35 tary table leaving the drill string between the table and boring tool in the hole. The mud used in rotary drilling for circulation settles around the drill string, "freezing" it in the hole and requiring a very expensive operation for its re-

40 moval. The present invention relates to a coupling which may be inserted at any desired point in the drill string and may be clutched to prevent uncoupling during normal operation of the string in both directions, but by longitudinal

45 movement of the string may be declutched to enable uncoupling by rotation in the same direction as in the boring operation. Although a specific use of the present invention has been described, it will be understood that it is not limited to such specific use.

The objects of this invention are to provide a coupling member for a screw joint having any or all of the following features:—Means to optionally position the male and female members

5 of the coupling so as to provide a clutch against rotary movement and thereby prevent uncoupling by rotation or to longitudinally position the members to enable rotary movement of the members of the coupling and uncoupling; means to releasably hold the members longitudinally 60 in clutched position and declutchable by a longitudinal pull on the tubular string in which the coupling is placed; and details of structure contributing to the before mentioned functional relationships.

65 These objects are accomplished by means of the embodiment of my invention illustrated in the accompanying drawing, in which:—

70 Fig. 1 is a longitudinal section through a coupling as seen on the irregular plane indicated by the lines 1—1 in Figs. 3 to 7 inclusive, the coupling being shown with parts disposed in clutched position; Fig. 2 is a view like Fig. 1 showing the parts in declutched position; Figs. 75 3 to 7 inclusive show sections indicated by planes 75 correspondingly numbered in Fig. 1; and Fig. 8 is a longitudinal view illustrating a drill string 80 provided with a number of right hand threaded tool joints, a drill bit and a safety coupling above the drill collar of a bit.

85 Referring more particularly to the drawing, A indicates the female member of my improved coupling and B the male member. The female member has a body 10 provided with a left hand threaded tapered bore 11 preferably having a fast thread and at the bottom end is provided with a right hand threaded pin 12 whereby it may be mounted in a corresponding box as desired in a string of drill pipe. At the upper end are jaws 14 forming a portion of a jaw clutch. 90 The male member comprises a tubular body 15 having a right hand threaded tapered box 16 at the upper end for connection to a pin or like member in the string of drill pipe. At its lower end, the body 15 is provided with jaws 17 for engagement between jaws 14 when the coupling is in contracted position as shown in Fig. 1. It is also provided with a shaft having a left hand threaded pin portion to be engaged with the box 11 of member A.

100 The body 15 is provided with a bore forming a continuation of the tapered bore 16. This bore is threaded at 18 and receives therein a detent barrel 19. The barrel may be locked in position by a set screw 20. Below the threaded portion 18 of the bore of member B is an enlarged portion 21. The barrel 19 spans the enlarged portion 21 and is provided with longitudinally extending slits 22. The slits extend 105 short of the ends of the barrel so that a barrel 110

is formed which may be expanded laterally. On the inner bore of the barrel are rounded catch portions 23 which project inwardly and have inclined faces. Adjacent the clutch jaws 17, the bore is threaded to receive a drive bushing 24 which may be held in position by a set screw 25. The bushing 24 is provided with key ways 26 extending longitudinally thereof.

Mounted within the bore of body 15 is a tubular shaft 27 threaded so that it may be engaged with the threads of box 11. It is also provided with splines 28 which are disposed within the key ways 26 so that shaft 27 is held against rotation with respect to the body 15 but is permitted sliding movement. The upper end of the shaft is enlarged externally to provide an abutment 29 whose lower face may engage the upper face of bushing 24 when the coupling is expanded as shown in Fig. 2. The bore of shaft 27 is threaded to receive a telescopic extension 30. The extension 30 has a tapered seat 31 forming a wedge adjacent its upper end, the upper end being externally enlarged to provide a slip fit with the bore of the upper portion of bushing 19 whereby a closed water course is formed through the coupling in both expanded and contracted positions. The upper portion of the bore of shaft 27 is enlarged to receive a detention ferrule 32 which is threaded therein and is provided with strips 33. The strips 33 rest against the wedge seat 31 at their outer ends and have inclined catch surfaces 34 to coact with the inclined catch surfaces 23 of the barrel.

Referring to Fig. 8, the drill string is illustrated as composed of stands C connected by right hand threaded tool joints D. A drill bit E is mounted in the string and connected thereto by my safety coupling F. With the parts of safety coupling F in positions shown in Fig. 1, the jaw clutch is in clutching position, jaws 14 being disposed between jaws 17. The shaft 27 is in retracted position being releasably held in this position by strips 33 engaging barrel 19 at the coacting inclined surfaces on catch portions 23 and 34. If it is desired to break the joint, an axial pull is exerted on the drill string causing barrel 19 to deflect outwardly and release strips 33, the inclined surfaces passing and enabling the shaft to be projected as shown in Fig. 2. In this position the jaw clutch is released and the coupling may be broken by turning the drill string to the right unscrewing pin 27 from the member A while the tool joint D and other couplings will tend to tighten but not unscrew. An adjustment can be made as to the tension required for release by turning the telescopic extension 30 so that the tips of strips 33 may be disposed at different positions on the wedge seat 31. Such adjustment may be found advisable depending upon the weight of the drill string above the coupling. The adjustment of the telescopic extension and seat 31 may be made by engagement of spanner slots 35 by a suitable tool inserted through the upper end of the bore of body 15 and screwing the extension 30 up or down at its threaded connection 36, with the shaft body to raise or lower the wedge seat and thereby decrease or increase the outside diameter of the strip member 32. The space 37 indicates clearance enabling movement of the extension. Thus, the pull required on the coupling to cause the detention means formed by barrel 19 and ferrule 32 to release, may be adjusted.

What I claim is:—

1. A longitudinally expansible and contractible coupling having threaded ends for connection to a string, said ends being threaded in the same direction, said coupling comprising a male member having a pin portion with a thread extending in a reverse direction and a female member having a box portion correspondingly threaded in relation to said pin portion for free engagement and release, one of said members having a shaft axially slidable for a limited distance and held against rotation therein and provided with one of said portions; side slide clutch means on said members for clutching engagement on contraction and declutching on expansion of said coupling; detention means between said shaft and its companion member to hold said shaft in retracted position with said members in clutched position and releasable by exertion of an axial pull on said expansible and contractible coupling to enable expansion of said members to declutched position, said pin portion and said box portion being positioned to be engageable in clutched position and to be threadedly meshed in declutched position. 80 85 90 95 100

2. A longitudinally expansible and contractible coupling having threaded ends for connection to a string, said ends being threaded in the same direction, said coupling comprising a male member having a pin portion with a thread extending in a reverse direction and a female member having a box portion correspondingly threaded in relation to said pin portion for free engagement and release, one of said members having a shaft axially slidable for a limited distance and held against rotation therein and provided with one of said portions; side slide clutch means on said members for clutching engagement on contraction and declutching on expansion of said coupling; said shaft being limited in its retraction to enable the pin portion to be positively abutted against and engaged with said box portion when said clutch means is disengaged; detention means between said shaft and its companion member to hold said shaft in retracted position with said members in clutched position and releasable by exertion of an axial pull on said expansible and contractible coupling to enable expansion of said members to declutched position, said pin portion and said box portion being positioned to be engageable in clutched position and to be threadedly meshed in declutched position. 105 110 115 120 125 130

3. A string for use in a well comprising section secured by threaded couplings having threads extending in one direction, a longitudinally expansible and contractible coupling comprising a male member having a pin portion with a thread extending in a reverse direction and a female member having a box portion correspondingly threaded in relation to said pin portion for free engagement and release, one of said members having a shaft axially slidable for a limited distance and held against rotation therein and provided with one of said portions; side slide clutch means on said members for clutching engagement on contraction and declutching on expansion of said coupling; detention means between said shaft and its companion member to hold said shaft in retracted position with said members in clutched position and releasable by exertion of an axial pull on said expansible and contractible coupling to enable expansion of said members to declutched position, said pin portion and said box portion being positioned to be 130 135 140 145 150

engageable in clutched position and to be threadedly meshed in declutched position.

4. A string for use in a well, comprising sections secured by threaded couplings having 5 threads extending in one direction, a longitudinally expansible and contractible coupling comprising a male member having a pin portion with a thread extending in a reverse direction and a female member having a box portion correspondingly threaded in relation to said pin portion for 10 free engagement and release, one of said members having a shaft axially slidale for a limited distance and held against rotation therein and provided with one of said portions; side slide 15 clutch means on said members for clutching engagement on contraction and declutching on expansion of said coupling; said shaft being limited in its retraction to enable the pin portion to be positively abutted against and threadedly meshed with said box portion when said clutch 20 means is disengaged; detention means between said shaft and its companion member having catch surfaces acting on one another, one of said surfaces being inclined to hold said shaft in retracted position with said members in clutched 25 position and releasable by exertion of an axial pull on said expansible and contractible coupling to enable expansion of said members to declutched position, said pin portion and said box portion being positioned to be engageable in both 30 positions; and means to adjust the lateral engaging positions of said surfaces whereby to vary the axial pull required for release.

15 5. A string for use in a well, comprising sections secured by threaded couplings having threads extending in one direction, a longitudinally expansible and contractible coupling comprising a male member having a pin portion with a thread extending in a reverse direction and a female member having a box portion correspondingly threaded in relation to said pin portion for 20 free engagement and release, one of said members having a shaft axially slidale for a limited distance and held against rotation therein and provided with one of said portions; side slide 25 clutch means on said members for clutching engagement on contraction and declutching on expansion of said coupling; said shaft being limited in its retraction to enable the pin portion to be positively abutted against and threadedly meshed with said box portion when said clutch 30 means is disengaged; detention means between said shaft and its companion member having catch surfaces acting on one another, one of said surfaces being inclined to hold said shaft in retracted position with said members in clutched position and releasable by exertion of an axial pull on said expansible and contractible coupling to enable expansion of said members to declutched position, said pin portion and said box portion being positioned to be engageable in both 35 positions.

20 6. A string for use in a well, comprising sections secured by threaded couplings having threads extending in one direction, a longitudinally expansible and contractible coupling comprising a male member having a pin portion with a thread extending in a reverse direction and a female member having a box portion correspondingly threaded in relation to said pin portion for 25 free engagement and release, one of said members having a shaft axially slidale for a limited distance and held against rotation therein and provided with one of said portions; side slide 30 clutch means on said members for clutching engagement on contraction and declutching on expansion of said coupling; said shaft being limited in its retraction to enable the pin portion to be positively abutted against and threadedly meshed with said box portion when said clutch 35 means is disengaged; detention means between said shaft and its companion member having catch surfaces acting on one another, one of said surfaces being inclined to hold said shaft in retracted position with said members in clutched position and releasable by exertion of an axial pull on said expansible and contractible coupling to enable expansion of said members to declutched position, said pin portion and said box portion being positioned to be engageable in both 40 positions.

35 45

expansion of said coupling; said shaft being limited in its retraction to enable the pin portion to be positively abutted against and threadedly meshed with said box portion when said clutch means is disengaged; detention means between said shaft and its companion member having catch surfaces acting on one another, one of said surfaces being inclined to hold said shaft in retracted position with said members in clutched position and releasable by exertion of an axial pull on said expansible and contractible coupling to enable expansion of said members to declutched position, said pin portion and said box portion being positioned to be engageable in both positions; and means to adjust the lateral engaging positions of said surfaces whereby to vary the axial pull required for release.

40 45 5. A string for use in a well, comprising sections secured by threaded couplings having threads extending in one direction, a longitudinally expansible and contractible coupling comprising a male member having a pin portion with a thread extending in a reverse direction and a female member having a box portion correspondingly threaded in relation to said pin portion for free engagement and release, one of said members having a shaft axially slidale for a limited distance and held against rotation therein and provided with one of said portions; side slide clutch means on said members for clutching engagement on contraction and declutching on expansion of said coupling; said shaft being limited in its retraction to enable the pin portion to be positively abutted against and threadedly meshed with said box portion when said clutch means is disengaged; detention means between said shaft and its companion member to hold said shaft in retracted position with said members in clutched position and releasable by exertion of an axial pull on said expansible and contractible coupling to enable expansion of said members to declutched position, said pin portion and said box portion being positioned to be engageable in both positions.
